FIG. 1 is a perspective view of a transportable refuse container showing my new design;

FIG. 2 is a side elevational view thereof, viewed from the side opposite that seen in FIG. 1;

FIG. 3 is a right end elevational view of my transportable refuse container as shown in FIG. 2;

FIG. 4 is a bottom plan view thereof;

FIG. 5 is a left end elevational view thereof; and

FIG. 6 is a perspective view similar to FIG. 1, illustrating a modified form of my new design in which the central band element included in the design illustrated in the prior figures is eliminated, the views otherwise being identical.

I claim:

The ornamental design for a transportable refuse container, as shown and described.
